UNITED STATES PATENT OFFICE.

FREDERICK W. VICKERY, OF LONDON, ENGLAND, ASSIGNOR TO POPE APPLIANCE CORPORATION, OF PORTLAND, MAINE, A CORPORATION OF MAINE.

AUTOMATIC REEL-TRANSFERRING MECHANISM FOR PAPER-WINDING MACHINES.

Application filed February 5, 1926, Serial No. 86,215, and in Great Britain February 5, 1925.

This invention relates to an automatic transfer mechanism for paper winding machines.

In high speed paper making machines, which deliver a web of paper at a rate of 300 or even 1100 feet per minute, the transference of the web from a winding reel which has been filled to a fresh empty one is a matter of difficulty, often involving a considerable waste of paper, and often causing a reel to be wound with a soft centre, which leads to difficulty in subsequent processes.

With a view of lessening the time occupied in the transfer, it is usual to support an empty reel in close proximity to the reel which is being filled, and to provide means for substituting it quickly for the filled reel. The paper web is fed to the winding reel over a drum, the reel resting on the paper on the drum, and an empty reel is brought into action by shifting it from a waiting position in which it is out of contact with the paper into a position in which it contacts with the paper, and then severing the web of paper and causing it to wrap upon the fresh reel. An earlier invention of the present applicant provides for performing these operations not only rapidly, but to a large extent automatically, the movement of the filled reel due to the accumulation of paper upon it, or movement resulting from the removal of the filled reel, being arranged to bring about the substitution of a fresh reel and if suitable preparations have been made the wrapping of the paper upon it.

The object of the present invention is to provide improved means for bringing about the severance of the paper and the wrapping of it on an empty reel wholly automatically. According to the invention this is effected by the aid of a jet of water. A suitable nozzle is supported near the winding reel, and is directed towards the position the reel will occupy at the instant it is desired to transfer the web to it; and the movements of the winding machine mechanism preceding or accompanying the shifting of a new reel into winding position are utilized to open a valve to admit water in predetermined quantity to the nozzle.

The invention further provides for adjusting the time at which water issues from the nozzle in relation to the instant at which the valve is operated, and also for rapidly

closing the valve after the desired interval, in order that water may not drop slowly and uselessly from the nozzle upon the web and cause breaks.

The invention consists in the combination and arrangement of parts set forth in the following specification and particularly pointed out in the claims.

Referring to the drawings:

Figure 1 is a side elevation of one embodiment of my invention.

Fig. 2 is a vertical sectional elevation taken through the dash pot 19.

Fig. 3 is a detail side elevation illustrating the cam mechanism.

Fig. 4 is a side elevation similar to Figure 1, illustrating a mechanism for operating a drain cock.

Fig. 5 is a side elevation embodying my invention as applied to another form of paper-winding machine.

Fig. 6 is a side elevation of a modified form of mechanism for actuating the water valve.

Fig. 7 is a plan view of a portion of the mechanism illustrated in Fig. 6.

Fig. 8 is a side elevation of a cam used in the embodiment of my invention illustrated in Fig. 6.

Like numerals refer to like parts throughout the several views of the drawings.

As is usual in paper winding machines of this type, the web of paper is fed to a reel 1 over a drum 2 which is rotated at a peripheral speed slightly higher than the speed of delivery of the web; and the reel 1 while being wound is carried in bearings 3 in a rocking frame 4 pivoted at 4' to the frame of the machine, which swings slowly outward as paper accumulates on the reel.

An empty reel 1^a is placed in readiness on the nearly horizontal part 5 of two supporting brackets 6, one on each side of the machine; and when the filled reel is about to be removed, the empty reel is pushed on the sloping part 7 of the brackets 6. It then rests against the cams 8 which are pivoted at 9 upon the rocking frame 4, and the outline of which forms with the surface 10 of the rocking frame a continuous curve leading to the bearings 3, the first portion of the curve being concentric with the pivot of the rocking frame. On the removal of the filled reel which is accomplished by a hoisting crane in a well-known manner and

as disclosed in my British Patent No. 223, 273, dated October 15, 1924, "Machine for winding paper webs," the rocking frame 4 falls back under gravity, cushioned by the dash pot 11, towards the drum 2, and the new reel 1 moves down the surface 7 into the bearings 3 and immediately afterwards comes into contact with the web of paper on the drum 2, which is still being wound upon the filled reel 1 by virtue of its continued rotation due to momentum while still held suspended by said hoisting crane.

Any convenient part of the movement of the rocking frame may be utilized for the purpose of the present invention, that is to bring about the spraying of water upon the new reel 1^a. In the construction illustrated part of the inward movement of the frame is utilized.

There is provided preferably on the rear side of the machine, a nozzle 12, directed at a slant towards the position the reel occupies immediately before it comes in contact with the drum. The nozzle is so placed (or several nozzles may be so provided) that when water is vigorously ejected from it (or them) the reel will be wetted through substantially its whole length. Water is supplied by the pipe 13 in which is a valve 14 normally held closed by a spring 15. The stem of the valve may be made with a head 16 so that it can be opened by hand when required. Its automatic opening is brought about by a lever 17 pivoted at 18, which bears at one end upon the valve stem and at the other end is linked to a dash pot 19 seen in further detail in Figure 2. The lever 17 is slotted, and there passes through it the hooked end of a rod 20 which is forked at 21 and engages over and can slide to and fro upon the pivot of the rocking frame 4. At its end the rod carries a stud 22 in position to be engaged by each of two cams 23 and 24 secured upon the rocking frame. The adjustable stop 25 in the lever 17 abuts upon the rod 20 when the lever is sufficiently turned. A spring 26 is compressed by the end of the outward movement of the rocking frame, and serves to give it an initial inward impulse when the filled reel is removed.

Since the turning off of the water as well as the turning on of the water is required to result automatically from the motion of the rocking frame, it is obvious that in the present arrangement which utilizes an inward movement of the frame for the purpose, the water must be turned off just before or just as the frame reaches the end of its inward movement, and therefore the water must be turned on a short time before the end of the movement. But the water is desired to issue from the nozzle 12 quite at the end of the movement, that

is to say just as the reel 1^a contacts with the drum 2; and it must cease to issue a short time after that instant. To introduce this delay between the operations of the valve 14 and the starting and stopping of the jet from the nozzle 12 there is provided in the course of the pipe 13 a reservoir 27.

If the valve were allowed to move slowly towards its completely closed position there would be an interval during which water passed through the valve at a very slow rate, insufficient to cause a vigorous jet at the nozzle 12, and consequently it would drip from the nozzle upon one part of the reel, needlessly wetting the web and causing breaks. To prevent this the dash pot 19 is designed as shown in Figure 2, the lower part of its bore being enlarged; so that as the piston nears the end of its stroke the resistance of the fluid suddenly ceases owing to its escape around the piston, and thus the valve is quickly closed by the spring 15 after being held wide open for the desired length of time.

The action of the apparatus is as follows:—As the rocking frame moves inward after the removal of the filled reel, under the action of spring 26 and gravity resisted by the dash pot 11, cam 23 engages stud 22 and pulls the rod 20, which through its hook turns the lever 17 and opens the valve 14. The water first fills the reservoir 27, and only when that is done can it issue from the nozzle 12. By adjustment of the size of the reservoir it is easy to adjust the exact instant at which the water issues. Quite near the end of the movement, for instance when the frame has reached the position indicated in dotted lines, the cam 24 engages the stud 22 and pulls the rod 20 further, so further turning the lever 17 and causing the stop 25 to abut upon the rod 20 and disengage its hook from the lever 17. The lever at once begins to return and the valve to close under the action of the spring 15 resisted by the dash pot 19, but the valve opening is not at first constricted. When the piston of the dash pot reaches the enlargement of its cylinder the valve is suddenly completely closed. The dash pot 19, therefore, determines the length of time during which water shall issue from the nozzle 12, and it is made adjustable in position for the purpose of altering this time.

A small drain cock 37 permits a constant leak from the reservoir 27, so that the reservoir is emptied by the time the next reel is filled and the operation has to be repeated. Instead of this constant leak, a drain cock may be provided which is opened automatically by the rocking frame on its outward movement and closed prior to the cycle of operations connected with the transference of the web to a new reel, as illustrated in

Fig. 4, in which a lever 38 fast to the pivot 4' is connected by a rod 39 to an arm 40 which operates the leak cock 37.

The water flung upon the reel 1^a is immediately carried down to the paper and wets it, with the double result that the web is severed from the part still being wound upon the removed reel and that it adheres to the new reel and begins to wind upon it.

10 In case of a breakage of paper, or for other reasons, it may be necessary to cause the above cycle of operations to occur independently of movement of the frame 4. For this purpose a cam 28 is loosely mounted 15 on the pivot of the frame, as seen in Fig. 3, and provided with a handle 29 by which it may be rotated; a single rotation of this cam by hand brings about the same results as a normal return movement of the rocking 20 frame.

Figure 5 shows the invention applied to another known form of paper winding machine of the same general type. In this case the empty reel 1^a is supported in arms 30 which can be rocked by hand by means of the pinion 31 and segment 32. The empty reel 1^a is placed in the position shown in dotted lines while the preceding reel 1 is being filled. When the filling is complete the 30 arms 30 are rocked to the position shown in full lines so that the reel 1^a is brought into contact with the paper web. It is at this instant that the web should be severed and wound upon the new reel.

35 For this purpose, according to the present invention, the arms 30 are fitted with a tail piece 33 which engages a gravity actuated tumbler 36 pivoted on a valve lever 34 when the arms 30 are rocked as above described, 40 and opens a valve 34' against the action of a spring 35.

When the paper has firmly wrapped itself upon the new reel 1^a, the arms 30 are turned back by hand so as to bring the new reel 45 into the bearings of the usual rocking frame 4. This movement of the arms should not affect the valve 34', the closing of which may be controlled in the manner already described. For this reason the valve is fitted 50 with the gravity-actuated tumbler 36, so that the tail piece 33 can move idly past it in one direction.

The particular mechanism employed to actuate the water valve or valves may be considerably modified. For instance it is not necessary that the valve shall be operated by the moving parts of the reeling mechanism provided its operation is caused at the proper time, as for example, the valve may 60 be opened and closed by means of a cam which can be caused to make a single revolution by the engagement of a clutch which connects it to the mechanism driving the drum 2. The function of the rocking frame 65 4, in this case, is only to put the clutch in

action, whereupon the cam is rotated and effects the desired cycle of operations at the desired instants of time and such a mechanism is illustrated in Figs. 6, 7 and 8, in which an arm 41 is fastened to a rocker 70 pivot 42 to which a rocker frame 43 is fastened and a connecting rod 44 is fastened to said arm 41. The rocking of the frame 43 through the pivot 42 imparts a rocking movement to the arm 41 and a reciprocatory movement to the connecting rod 44. A shoulder 45 is provided upon the outer end of the connecting rod 44 which, at the proper time, engages a pawl 46 causing the same to be lifted out of engagement with a clutch 80 guide plate 47 and this allows a spring 48, see Fig. 8, to pull the guide plate 47, together with a roller 49 up the incline 50 of a fixed clutch member 51 and thus bind a sprocket wheel 52 between the fixed clutch member 51 and a fixed cam 53, thus causing the cam shaft 54 to revolve and operate a water valve 55 through a bell-crank lever 58. The rod 44 after lifting the pawl 46 continues its travel toward the left, Fig. 6, until it arrives upon a pin 56 which allows the pawl 46 to return to the position shown in Fig. 6, so that as the clutch guide plate 47 comes in contact with it, its movement is arrested, thus carrying the roller 49 down 90 into a larger part of a slot 57 in the fixed member 51, whereupon the cam shaft stops and will rest in this position until the pawl 46 is again operated by the rod 44. The clutch guide plate 47 is connected to the 100 fixed clutch member 51 by the spring 48 which operates to force the roller 49 up the slot 57 as long as it is not prevented from so doing by the action of the pawl 46.

I claim:—

1. An automatic reel transferring mechanism for paper winding machines having, in combination, a drum, a pair of winding reels, mechanism to position one of said winding reels in operative relation to a web of paper on said drum, while the other winding reel is in inoperative relation thereto, said mechanism being adapted, when the operatively positioned reel is removed therefrom, to automatically receive and position the other of said reels in operative relation to the web of paper on said drum, a conductor for water, and means actuated by said reel positioning mechanism to cause water from said conductor to be distributed upon said web of paper at a predetermined time, whereby said web may be severed and caused to wrap upon the empty reel.

2. An automatic reel transferring mechanism for paper winding machines having, in combination, a drum, a pair of winding reels, mechanism to position one of said winding reels in operative relation to a web of paper on said drum, while the other

winding reel is in inoperative relation thereto, said mechanism being adapted, when the operatively positioned reel is removed therefrom, to automatically receive and position 5 the other of said reels in operative relation to the web of paper on said drum, means to direct water against said empty reel as it comes into operative position and into contact with said web, a shut-off for said 10 water and mechanism to operate said shut-off at predetermined times, whereby said web may be automatically severed and caused to wrap upon the empty reel.

3. An automatic reel transferring mechanism for paper winding machines having, in combination, a drum, a pair of winding reels, a rocking frame upon which one of said winding reels may be rotatably mounted while positioned to contact with a web 15 of paper on the drum, a frame upon which the other of said reels may be positioned while empty, the rocker frame having a cam-shaped edge adapted to engage the empty winding reel and sustain it while 20 said web is being wound upon the other winding reel and the rocker frame moving outwardly from the drum, guiding surfaces on said frame to guide the empty reel into rotatable position on the rocker frame 25 after the full winding reel has been removed from the rocker frame and said rocker frame is moved inwardly toward the frame, a conductor for water, and means actuated by said rocker frame to 30 control the discharge of said water at a predetermined time upon said empty reel, whereby said web of paper may be severed and caused to wrap upon said empty reel.

4. An automatic reel transferring mechanism for paper winding machines having, in combination, a drum, a pair of winding reels, mechanism to position one of said winding reels in operative relation to a web 40 of paper on said drum, while the other winding reel is in inoperative relation thereto, said mechanism being adapted, when the operatively positioned reel is removed therefrom, to automatically receive and position 45 the other of said reels in operative relation to the web of paper on said drum, a conductor for water, means actuated by said reel positioning mechanism to cause water from said conductor to be distributed upon 50 said web of paper when an empty reel comes in contact therewith, whereby said web of paper may be severed and caused to wrap upon said empty reel, and means for timing the action of said last-named means.

5. An automatic reel transferring mechanism for paper winding machines having, in combination, a drum, a pair of winding reels, a rocker frame upon which one of said winding reels may be rotatably mounted while positioned to contact with a web 60

of paper on the drum, a frame upon which the other of said reels may be positioned while empty, the rocker frame having a cam-shaped edge adapted to engage the empty winding reel and control it while 70 said web is being wound upon the other winding reel and the rocker frame moving outwardly from the drum and guiding surfaces on said frame to guide the empty reel into rotatable position on the rocker frame 75 after the full winding reel has been removed from the rocker frame and said rocker frame is moved inwardly toward the frame, a nozzle to direct water against said empty reel as it is being moved into operative position and into contact with said web, a shut-off valve for said water, and mechanism operated by said rocker frame during 80 its inward movement, to operate said shut-off valve at predetermined times, whereby 85 said web may be automatically severed and caused to wrap upon the empty reel.

6. An automatic reel transferring mechanism for paper winding machines having, in combination, a drum, a pair of winding reels, a rocker frame upon which one of said winding reels may be rotatably mounted while positioned to contact with a web of paper on the drum, a frame upon which the other of said reels may be positioned while empty, the rocker frame having a cam-shaped edge adapted to engage the empty winding reel and sustain it while 90 said web is being wound upon the other winding reel and the rocker frame moving outwardly from the drum, guiding surfaces on said frame to guide the empty reel into rotatable position on the rocker frame after the full 95 winding reel has been removed from the rocker frame and said rocker frame is moved inwardly toward the frame, a nozzle to direct water against said empty reel as it is being moved into operative position and into contact with said web, a shut-off valve for said 100 water, and mechanism, including a dash-pot, operated by said rocker frame during its inward movement to operate said shut-off valve at predetermined times, whereby 105 said web may be automatically severed and caused to wrap upon the empty reel.

7. An automatic reel transferring mechanism for paper winding machines, having, in combination, a drum, a pair of winding reels, a rocker frame upon which one of said winding reels may be rotatably mounted while positioned to contact with a web of paper on the drum, a frame upon which the other of said reels may be positioned while empty, the rocker frame having a cam-shaped edge adapted to engage the empty winding reel and hold it stationary while 110 said web is being wound upon the other winding reel and the rocker frame moving outwardly from the drum, guiding surfaces on said frame to guide the empty reel into 115

rotatable position on the rocker frame after the full winding reel has been removed from the rocker frame and said rocker frame is moved inwardly toward the frame, a nozzle to direct water against said empty reel as it is being moved into operative position and into contact with said web, a spring-actuated valve to control the supply of water, a lever therefor, a slidable rod detachably connected to said lever and a cam on said rocker frame adapted to impart a reciprocatory motion to said rod, whereby said valve may be operated at predetermined times to operate said valve and said web automatically severed and caused to wrap upon the empty reel.

8. An automatic reel transferring mechanism for paper winding machines having, in combination, a drum, a pair of winding reels, mechanism to position one of said winding reels in operative relation to a web of paper on said drum, while the other winding reel is in inoperative relation thereto, said mechanism being adapted, when the operatively positioned reel is removed therefrom, to automatically receive and position the other of said reels in operative relation to the web of paper on said drum, means to direct water against said empty reel as it is being moved into operative position and into contact with said web, a shut-off for said water, and mechanism, including a dash-pot, to operate said shut-off at predetermined times, whereby said web may be automatically severed and caused to wrap upon the empty reel.

9. An automatic reel transferring mechanism for paper winding machines having, in combination, a drum, a pair of winding reels, a rocker frame upon which one of said winding reels may be rotatably mounted while positioned to contact with a web of paper on the drum, a frame upon which the other of said reels may be positioned while empty, the rocker frame having a cam-shaped edge adapted to engage the empty winding reel and hold it while said web is being wound upon the other winding reel and the rocker frame moving outwardly from the drum, guiding surfaces on said frame to guide the empty reel into rotatable position on the rocker frame after the full winding reel has been removed from the rocker frame and said rocker frame is moved inwardly toward the frame, a nozzle to direct water against said empty reel as it is being moved into operative position and into contact with said web, a shut-off valve for said water, a reservoir interposed between said nozzle and valve, an outlet cock in said reservoir adapted to empty it between successive operations of the rocker frame, means operated by said rocker frame to open and close said outlet cock, and mechanism operated by said rocker frame during its inward movement to operate said shut-off valve at predetermined times, whereby said web may be automatically severed and caused to wrap upon the empty reel.

matically severed and caused to wrap upon the empty reel.

10. An automatic reel transferring mechanism for paper winding machines having, in combination, a drum, a pair of winding reels, a rocker frame upon which one of said winding reels may be rotatably mounted while positioned to contact with a web of paper on the drum, a frame upon which the other of said reels may be positioned while empty, the rocker frame having a cam-shaped edge adapted to engage the empty winding reel and hold it while said web is being wound upon the other winding reel and the rocker frame moving outwardly from the drum, guiding surfaces on said frame to guide the empty reel into rotatable position on the rocker frame after the full winding reel has been removed from the rocker frame and said rocker frame is moved inwardly toward the frame, a nozzle to direct water against said empty reel as it is being moved into operative position and into contact with said web, a shut-off valve for said water, a reservoir interposed between said nozzle and valve, an outlet cock in said reservoir adapted to empty it between successive operations of the rocker frame, means operated by said rocker frame to open and close said outlet cock, and mechanism operated by said rocker frame during its inward movement to operate said shut-off valve at predetermined times, whereby said web may be automatically severed and caused to wrap upon the empty reel.

11. In a paper winding machine the combination with a drum, a winding reel supported near to but out of co-operative relation with said drum, transfer mechanism for bringing said winding reel into co-operative relation with a web of paper on said drum, a nozzle directed towards the position occupied by said winding reel on coming into co-operative relation with said drum, and means automatically actuated in the sequence of operations of said transfer mechanism and as said reel comes into contact with said web of paper for supplying water to said nozzle and cutting it off therefrom.

12. In a paper winding machine the combination with a drum, a rocking frame for supporting a winding reel in contact with a web of paper on said drum, and transfer mechanism for bringing an empty winding reel into co-operative relation with the web upon said drum and into said rocking frame, of a conduit for directing water upon an empty reel on its coming into co-operative relation with the web, and means automatically actuated at each transfer for supplying water to and shutting it off from said conduit.

13. In a paper winding machine the combination of a drum, a rocking frame rocked in the process of bringing an empty reel into

- co-operative relation with said drum, a nozzle for directing water upon an empty reel on its coming into co-operative relation with said drum, means actuated by said rocking frame controlling the supply of water to said nozzle, and means for causing the issue of water from said nozzle to lag behind the actuation of said control means by said rocking frame.
- 10 14. In a paper winding machine the combination of a drum, a rocking frame rocked in the process of bringing an empty reel into co-operative relation with said drum, a nozzle for directing water upon an empty reel on its coming into co-operative relation with said drum, a cock actuated by said rocking frame controlling the supply of water to said nozzle, a container interposed between said cock and said nozzle, and means for emptying said container between the closing of said cock and its next opening.
- 15 15. In a paper winding machine the combination of a drum, a rocking frame rocked in the process of bringing an empty reel into co-operative relation with said drum, a nozzle for directing water upon an empty reel
- 20 on its coming into co-operative relation with said drum, a cock actuated by said rocking frame controlling the supply of water to said nozzle, a container interposed between said cock and said nozzle, and means for emptying said container between the closing of said cock and its next opening.
- 25 16. In a paper winding machine the combination with a drum, a carrier for supporting a winding reel in co-operative relation with a web of paper on said drum, means for supporting a winding reel out of co-operative relation with said drum near to the position of co-operative relation, automatic means operating upon the removal of a filled reel from said carrier to position said carrier to receive an empty reel and support it in co-operative relation with said drum, to transfer an empty reel to said carrier, and means to discharge water upon said empty reel as the latter comes into contact with said web of paper, whereby said web is severed and caused to wind upon said empty reel.
- 30 35 40 45
- In testimony whereof I have signed my name to this specification.

REDERICK W. VICKERY.
